UNITED STATES PATENT OFFICE.

HENRY L. RECKARD, OF HARTFORD, CONNECTICUT.

PHOTOMECHANICAL PROCESS OF ENGRAVING.

962,098.

Specification of Letters Patent. Patented June 21, 1910.

Application filed October 5, 1909. Serial No. 521,147.

To all whom it may concern:

Be it known that I, HENRY L. RECKARD, a citizen of the United States, residing at Hartford, county of Hartford, State of Connecticut, have invented certain new and useful Improvements in Photomechanical Processes of Engraving, of which the following is a full, clear, and exact description.

My invention relates to photo-mechanical engraving of designs having modulations of light and shade, and consists in a simple and accurate method of producing such engravings on metal surfaces for printing.

The following is a description of an embodiment of my invention, reference being had to the accompanying drawings, which illustrate various steps in the process, and in which,—

Figure 1 illustrates a design having modulated portions, such for instance, as appear in a wash drawing. Inasmuch as the requirements of the Patent Office as to drawings, do not permit the use of such drawings, the variations are shown by shade lines. These lines are, however, intended to represent continuous shadings or modulations. Fig. 2 is a dry plate photographic negative of Fig. 1, the modulations here also being shown by shade lines for the reasons above stated. Fig. 3 is a wet plate negative of Fig. 2, made through a suitable screen by means of a camera, the result being a wet plate dotted positive of Fig. 1. Fig. 4 is a lithographic stone having a lithograph made thereon from the plate of Fig. 3. Fig. 5 is a transfer made from the stone of Fig. 4, trimmed down so as to correspond with the design of Fig. 1. Fig. 6 is a zinc plate to which the transfer of Fig. 5 has been applied and subsequently removed so as to leave the ink thereon, and which has been subsequently treated as hereinafter described. Fig. 7 represents a roller to be engraved, about to be rolled over the zinc plate of Fig. 6 after the same has been etched.

The following description will refer more particularly to the drawings.

In Figs. 3, 4, 5 and 6, the dimensions of the dots and the spaces between them, in order to permit of illustration, are enlarged, so as to be greater than they would be in practice, as will be understood by those familiar with the use of half tone and similar screens.

In carrying out the invention, the original of the design to be engraved must show the

modulations as represented by the shade lines in Fig. 1. Such original may be a wash drawing, a colored picture or print or a photograph, preferably a wash drawing 1 60 on white paper 2. My process is adapted to modulated printing in one color or modulated printing in several superimposed colors.

When the design is to be printed in one 65 color, a dry plate photograph 3 (Fig. 2) is first made, that is, a negative of the original design. A dry plate is used because it reproduces more accurately the modulations of the original design. From that dry plate 70 negative photograph a wet plate positive 4 (Fig. 3) is made through a suitable screen by means of a camera, the preferred form of screen being a dotted screen in which small round dots located very close to one another 75 appear clear and transparent, the field around the dots being opaque. The ordinary half-tone screen, however, may be used. A positive made with a dotted screen will show the design and all its modifications of light 80 and shade in opaque dots A of varying sizes as in Fig. 3 and I term this dotted positive the "photograph". By means of this positive photograph I produce a photolithograph (Fig. 4) upon a stone or similar photolithographic surface 5 in the ordinary manner. From this photolithograph I produce a transfer 6, (Fig. 5) or, if the design is to be repeated upon the surface to be engraved, a number of transfers equal to the 90 number of repeats necessary. I then apply to the transfer, or, if the designs are to be repeated, the transfers suitably mounted on a sticking up sheet, a thin sheet of zinc B (Figs. 6 and 7), preferably about 1/100 of 95 an inch thick. I then remove the transfer paper in the ordinary way used in lithography, leaving the ink upon the zinc sheet. I then etch the sheet. In etching I first roll the zinc sheet with an inked roller until the 100 inked portions become strong and sharp, and then powder it with fine asphalt. I then dust it clean with cotton or a brush, preferably cotton. I then warm it until the asphalt is melted into the ink, forming a 105 hard smooth acid resist. I then coat the exposed edges C and back of the zinc sheet with asphalt varnish, except a space about 1/16 of an inch at the beginning of the design corresponding to the space D. I then immerse the zinc plate in dilute nitric acid, 110 about 16 parts of water to one part of nitric

acid, until the exposed surfaces are eaten away to a depth of about $2/1000$ of an inch, so that it may be inked with an acid resisting ink applied with a smooth ink roller. 5 The etching must be of such depth that the inking roller will deposit no ink in the depths of the plate. It is a type surface and not a planographic surface. The design to be engraved on the roller is in the depths of 10 the plate. After etching the plate, the acid resist and asphalt are washed off with turpentine. One edge is then cut off at E on a line with the remote edge or end of the design. The plate is then inked with a stiff 15 acid-resisting ink and placed on a flat level table F, the cut edge of the plate corresponding exactly with the edge of the table, the plate being securely clamped by the clamp F' in that position. A clean strip of 20 paper G is then placed on the plate in a line parallel with the edge or beginning of the design and about $1/16$ of an inch away from the design, being outside the etched line D which was not varnished. The 25 sticky ink holds the paper in place. The roller H is then lowered onto the strip of paper G, which provides a perfectly clean rest for the roller, and pressure applied. The roller H is then caused to revolve, rolling 30 over the surface of the inked plate, and the ink is thereby transferred from the plate to the surface of the roller. The design shows in clean copper dots on the roller, the field around the design and around the dots 35 being covered with acid-resisting ink. The roller is next etched. In doing this it is powdered with fine asphalt powder applied with soft cotton, and then dusted clean with a clean piece of cotton. The asphalt ad- 40heres to the inked parts but does not adhere to the clean copper. The roller is then warmed from the inside until the asphalt blends with the ink. When cool, the roller is immersed in a bath of acid, being con- 45tinually rotated to assure an even action. I prefer to use as an etching solution chlorid of iron two parts, water one part. The etching solution eats out the exposed dots, leaving the design engraved in intaglio dots, 50 of varying size. After etching, the roller is cleaned and is ready for intaglio printing.

When it is desired to engrave rollers for multi-color printing in two or more superimposed colors, the original must be a colored picture or printing. Three colors are 55 ordinarily used in such printing, in accordance with the well-known three color process. In carrying out my invention in connection with such work, three dry tri-color 60 plate negatives are made through color filters, one negative for red, one for yellow and one for blue. From each of these neg- 65 atives a wet plate positive is made through a suitable screen, preferably the form of dotted screen before described, although a half-

tone screen may be used. From each of these positives a roller is engraved in the same manner as hereinbefore described. By these rollers, when in proper alinement, the printing is done, the proper rollers being 70 furnished respectively with yellow color, red color and blue color. These colors are delivered by the rollers on to the fabric, one color over the other, producing a picture in the various colors and shades of color shown 75 in the original design by means of the blending in varying proportions of the three primary colors.

Instead of transferring the ink from the transfers to the zinc sheet and then to the 80 roller, it may be transferred directly from the transfers to the roller to be engraved. It is preferable, however, to transfer it through the medium of the zinc sheet, since by so doing a permanent copy of the design 85 is ready to be applied to the roller with little trouble is obtained, and further, if by chance the ink is rubbed or other accident happens so as to render the design as impressed upon the roller imperfect before it is engraved, 90 the zinc sheet can be readily cleaned and re-inked, with the expenditure of much less time and labor than is necessary to make new transfers, and particularly to make new transfers and stick them up in proper 95 relation upon a lay-out.

What I claim is:

1. In a photo-mechanical process of engraving metal, the improvement which consists in photographing a design having modulations of light and shade by means of a dry plate, photographing the design carried by said dry plate through a screen and obtaining thereby a dotted positive of the original, producing a photo-lithograph from 100 said dotted positive, producing a transfer from said photo-lithograph, transferring the ink from said transfer to a metal surface and etching said metal surface, inking said metal surface and transferring the ink 105 therefrom to a metal roller and etching said metal roller.

2. In a photo-mechanical process of engraving metal, the improvement which consists in photographing a design having modulations of light and shade by means of a dry plate, photographing the design carried by said dry plate through a screen upon a wet plate, and obtaining thereby a dotted positive of the original, producing a photo-lithograph from 110 said dotted positive, producing a transfer from said photo-lithograph, transferring the ink from said transfer to a metal surface and etching said metal surface, inking said metal surface and transferring the ink 115 therefrom to a metal roller and etching said metal roller.

3. In a photo-mechanical process of engraving metal, the improvement which consists in photographing a design having su- 120

perimposed colors and modulations of light and shade through color filters and by means of dry plates, photographing the designs carried by the several dry plates through a screen upon wet plates, and obtaining thereby dotted positives thereof, producing a plurality of photo-lithographs one from each of said dotted positives, pro-

lithographs, transferring the ink from said transfers to metal surfaces and etching said metal surfaces, inking said metal surfaces, transferring the ink therefrom to metal rollers and etching said rollers.
